ELECTRICAL APPARATUS

Leslie Herbert Bedford, Lionel Jofeh and Walter Henry Stevens, London, England, assignors to A. C. Cossor Limited, London, England, a British company

Original application May 8, 1939, Serial No. 272,508. Divided and this application September 19, 1942, Serial No. 459,018. In Great Britain May 10, 1938

6 Claims. (Cl. 250—157)

The invention relates to an electromagnetic system for the deflection of the electron beam of a cathode ray tube in two mutually perpendicular directions.

The present application is a division of our prior application Serial No. 272,508, filed May 8, 1939, now Patent No. 2,336,837.

An object of the invention is to provide a robust and compact assembly of deflection coils for the two directions of deflection.

A further object is to minimize mutual interference between the currents passed through the deflection coils and mutual interference between the electromagnetic deflection fields produced thereby.

A preferred arrangement embodying the invention is illustrated in the accompanying drawing, in which Figure 1 shows a perspective view of an electromagnetic deflecting apparatus surrounding the neck of a cathode ray tube suitable for a television receiver and Figure 2 is a diagrammatic sectional view of Figure 1 taken on the plane of the central lamination 11.

The electron gun (which includes the cathode) and the fluorescent screen are not shown, but the former is assumed to be situated below, and the latter above, the assembly shown, so that the electron beam passes upward through the neck 1 of the cathode ray tube.

The two coils 7 produce one of the electromagnetic deflection fields and the coils 8 produce the other. Each of these fields is of the kind comprising a central flux path passing transversely through the neck of the tube and comprising two symmetrical side paths passing on mutually opposite sides of the neck of the tube.

The coils 7 are bent around to lie in contact with the former 6 which is a sleeve of insulating material closely surrounding the neck of the tube. The central flux path of the field of the coils 7 passes through the neck of the tube in the direction of the common axis 7' of the coils 7, see Figure 2.

The coils 8 have their centres substantially on the common axis 7' of the coils 7, but their own axes are perpendicular to the axis of the coils 7. The central flux path of the field of the coils 8 passes through the neck of the tube in the direction 8' parallel to the axes of the coils 8, see Figure 2.

The part of the magnetic circuit of the coils 8 external to the tube is formed by laminations 11 in the form of complete rectangles of ferromagnetic materials. These laminations are spaced apart by wooden spacers 12.

The part of the magnetic circuit of the coils 7 external to the tube is formed by laminations 9a, 9b, 9c of ferromagnetic material. These are divided, the part 9a, in the form of a complete rectangle, being placed on the end of the assembly 5 nearer the fluorescent screen, and the other part 9b, 9c, forming substantially a rectangle, being placed on the end of the assembly nearer the cathode. The part 9b, 9c is subdivided into two 10 U-shaped parts by the provision of gaps in the region of the ends of the central flux path of the magnetic circuit belonging to the coils 7. These gaps minimize the short-circuiting of the magnetic circuit of the coils 8. The laminations 15 9a, 9b, 9c, are spaced from the two outer laminations 11 by wooden spacers 10, and are thus arranged at the ends of the coils 7.

From Figure 2 it will be seen that the central flux path for coils 7 is directed along the axis 7' of these coils, while the central flux path for the coils 8 is directed along the axis 8' parallel to the axes of these coils but at right angles to the axis 7'. The flux from the central path along axis 7' divides, and a portion represented by the 20 link of dotted arrows 7a forms one side path for this magnetic circuit and the other portion represented by the link of dotted arrows 7b forms the other side path for this circuit, these side paths being completed partly through lamination 9a. In 25 a like manner, the flux from the central path along axis 8' divides, a portion going through one coil 8 surrounding one leg of lamination 11 and the other portion going through the other coil 8 surrounding the opposite leg of the lamination.

30 By virtue of the arrangement of the coils 8 in relation to the coils 7, the electromagnetic pick-up of the coils 8 resulting from current changes in the coils 7 is neutralized. This is due to the fact that coils 7 surround the central flux path of 35 one deflecting magnetic circuit whereas coils 8 are linked separately with the side paths only of the other deflecting magnetic circuit. The coils 8 may be arranged for adjustment in the direction 40 of their axes so as to provide for accurate adjustment of this neutralisation.

The coils 8 should preferably be enclosed in electrostatic screens to minimise electrostatic interference between the two pairs of coils.

45 The coils 7 should preferably be so electrically connected in their circuit as to be operated in respect to alternating current, symmetrically about earth. This is diagrammatically indicated in the drawing by showing the terminals 13 of the circuit for coils 7 connected by leads one to each

coil, and by showing the other leads from each coil connected together and earthed at 14.

When the deflection system shown and described is used for television scanning, the coils 8 are employed to produce the lower frequency or "frame" deflection and the coils 7 to produce higher frequency or "line" deflection. The laminations 9 are preferably then made of "Rhometal" and the laminations 11 of "Stalloy."

The ratio of permeability at line frequency to permeability at frame frequency is substantially higher for "Rhometal" than for "Stalloy."

It will be understood that features of this invention are applicable not only to cathode ray tubes having fluorescent screens but also to other types such as iconoscopes and electron beam deflection valves.

We claim:

1. In a cathode ray tube having a compact electromagnetic deflection system including magnetic circuits for controlling the electron beam in two mutually perpendicular directions of deflection, each of which comprises a central flux path passing through the tube and two side paths for the flux which pass on mutually opposite sides of the tube, the combination of coils for producing the flux to control the deflection in one direction positioned about a common axis and on opposite sides of the tube about the central flux path of a first magnetic circuit, and coils for producing the flux to control the deflection in a perpendicular direction positioned on side flux paths of a second magnetic circuit with their centres substantially on said common axis at opposite sides of the tube and with their axes perpendicular to said common axis.

2. In a cathode ray tube having a compact electromagnetic deflection system including magnetic circuits for controlling the electron beam in two mutually perpendicular directions of deflection, each of which comprises a central flux path passing through the tube and two side paths for the flux which pass on mutually opposite sides of the tube, the combination of coils for producing the flux to control the deflection in one direction positioned about a common axis and on opposite sides of the tube about the central flux path of a first magnetic circuit, and coils for producing the flux to control the deflection in a perpendicular direction positioned on side flux paths of a second magnetic circuit with their centres substantially on said common axis at opposite sides of the tube and with their axes perpendicular to said common axis, the coils for producing electromagnetic flux in said second magnetic system being moveably supported for adjustment in the direction of their axes.

3. In a cathode ray tube having a compact electromagnetic deflection system including magnetic circuits for controlling the electron beam in two mutually perpendicular directions of deflection, each of which comprises a central flux path passing through the tube and two side paths for the flux which pass on mutually opposite sides of the tube, the combination of coils for producing the flux to control the deflection in one direction positioned about a common axis and on opposite sides of the tube about the central flux path of a first magnetic circuit, means for maintaining the electrical central point of said coils at a

constant potential, and coils for producing the flux to control the deflection in a perpendicular direction positioned on side flux paths of a second magnetic circuit with their centres substantially on said common axis at opposite sides of the tube and with their axes perpendicular to said common axis.

4. In a cathode ray tube having a compact electromagnetic deflection system including magnetic circuits for controlling the electron beam in two mutually perpendicular directions of deflection, each of which comprises a central flux path passing through the tube and two side paths for the flux which pass on mutually opposite sides of the tube, the combination of coils for producing the flux to control the deflection in one direction positioned about a common axis and on opposite sides of the tube about the central flux path of a first magnetic circuit, means for grounding the centre point of said coils, and coils for producing the flux to control the deflection in a perpendicular direction positioned on side flux paths of a second magnetic circuit with their centres substantially on said common axis at opposite sides of the tube and with their axes perpendicular to said common axis.

5. In a cathode ray tube having a compact electromagnetic deflection system including magnetic circuits for controlling the electron beam in two mutually perpendicular directions of deflection, each of which comprises a central flux path passing through the tube and two side paths for the flux which pass on mutually opposite sides of the tube, the combination of coils for producing the flux to control the deflection in one direction positioned about a common axis and on opposite sides of the tube about the central flux path of a first magnetic circuit, coils for producing the flux to control the deflection in a perpendicular direction positioned on side flux paths of a second magnetic circuit with their centres substantially on said common axis at opposite sides of the tube and with their axes perpendicular to said common axis, a ferromagnetic path for said second magnetic circuit, and a divided ferromagnetic path for said first magnetic circuit, the divided portions of which being oppositely displaced from the second magnetic circuit in the direction parallel to the electron beam path.

6. In a cathode ray tube having a compact electromagnetic deflection system including magnetic circuits for controlling the electron beam in two mutually perpendicular directions of deflection at substantially different frequencies of field flux, each of which comprises a central flux path passing through the tube and two ferro-magnetic paths external of the tube for the flux which passes on mutually opposite sides of the tube, the combination of ferromagnetic means providing external paths for each of said magnetic circuits, the external ferromagnetic paths of the magnetic circuit carrying the higher frequency of field flux having a substantially greater ratio of permeability at high frequencies to permeability at low frequencies than have the external ferromagnetic paths of the magnetic circuit carrying the field flux of lower frequency.
